Patented April 12, 1904.

UNITED STATES PATENT OFFICE.

ALCIBIADES G. PSIABI, OF NEW YORK, N. Y.

CIGARETTE OR CIGAR BOX.

SPECIFICATION forming part of Letters Patent No. 757,225, dated April 12, 1904.

Application filed June 20, 1903. Serial No. 162,343. (No model.)

To all whom it may concern:

Be it known that I, ALCIBIADES G. PSIABI, a citizen of the United States, and a resident of the city of New York, borough of Manhattan, in the county and State of New York, have invented a new and Improved Cigarette or Cigar Box, of which the following is a full, clear, and exact description:

This invention relates to improvements in cigarette or cigar boxes of the kind in which the cigarettes or cigars are originally packed for sale; and an object is to provide a box of novel construction and having a receptacle for holding matches furnished with each package.

15 I will describe a cigarette or cigar box embodying my invention and then point out the novel features in the appended claims.

Reference is to be had to the accompanying drawings, forming a part of this specification,

20 in which similar characters of reference indicate corresponding parts in all the figures.

Figure 1 is a perspective view of a box embodying my invention. Fig. 2 is a sectional view thereof, and Fig. 3 is a plan view of the inner or sliding member with the parts spread out to clearly show the construction.

The box comprises a casing 1, of cardboard or other suitable material, closed at one end and open at the other. In a side wall of this

30 casing an opening 2 is formed, through which matches may be drawn or discharged. The inner member, arranged to slide in the casing, consists of a tray portion 3, in which cigarettes or the like are to be placed, and at the outer end the said sliding portion is provided with a closing-flap 4 for closing the end of the box when the tray is moved inward. On the opposite or inner end of the tray the bottom portion thereof has an extension 5, a portion

35 of which immediately at the rear end of the end wall 7 of the tray forms the bottom wall of a match-receptacle. A portion 8 of said extension forms a side wall of the receptacle, and the part 5, or body part, is designed to fold over a portion of the tray, as clearly indicated in

40 Fig. 1. This extension 5 has at its ends lateral flaps 9, designed to engage against the sides of the tray. One side wall of the tray portion has an extension 10, forming the end wall of

45 the match-receptacle, the opposite end of the

receptacle being left open. One side wall of the tray has a sanded part or portion 11, on which the matches are to be scratched.

In the operation when it is desired to remove a match the sliding member is to be drawn out until the open end of the match-receptacle registers with the opening 2, and it will be noted that the said opening 2 is near the lower edge of the casing, so when one or more matches remain in the box the same may be easily dropped out by turning the box practically edgewise. When the box is tilted, the cigarettes or the like will be prevented from falling out by means of the extension 5 and also by means of the closure-flap 4, the end of which may be engaged underneath said extension.

Having thus described my invention, I claim as new and desire to secure by Letters Patent—

1. A box for the purpose described, comprising a casing member having an opening at one side, and a sliding member having a match-receptacle at its inner end, the said receptacle having an open end arranged for registering with the side opening of the casing when said sliding member is partly drawn out.

2. In a box, the combination with a casing member having an opening at one side, of an inner sliding member comprising a tray portion, an extension from said tray portion adapted to fold over the tray, the said extension also forming the top, bottom and a side wall of a match-receptacle at the inner end of the tray, and an extension on one of the side walls of the tray, forming an end wall of said receptacle, the opposite end of said receptacle being open to register with the side opening of the casing.

3. In a box, the combination with a casing member having an opening in one side near the lower edge, of an inner sliding member comprising a tray portion, an extension from the bottom of said tray portion adapted to fold over the tray, the said extension forming the top, bottom and a side wall of a match-receptacle at the inner end of the tray, and flaps on said extension for engaging against the sides of the tray.

4. In a box, the combination with a casing closed at one end and open at the other end,

- 2
- the said casing being provided with an opening in one of its side walls, of an inner sliding member comprising a tray, an end-closure for said tray, an extension at the inner end of said tray adapted to fold over the tray, and also to form the walls of a match-receptacle at the rear end of the tray, and lateral flaps on said extension for engaging against the sides of the tray.
- 10 5. In a box, the combination with a casing having an opening through one of its side walls, one end of said casing being closed and the other end open, of an inner sliding member having a tray portion, a flap at one end of the tray forming a closure, an extension on the opposite end of the tray having a portion

forming the bottom wall of a match-receptacle, a portion forming the side wall of the receptacle, a portion forming the top wall of the receptacle, and a portion extended over the 20 tray and having lateral flaps at its end for engaging the sides of the tray, said match-receptacle being open at one end and closed at the other end.

In testimony whereof I have signed my name 25 to this specification in the presence of two subscribing witnesses.

ALCIBIADES G. PSIABI.
